CLAIM

The ornamental design for a cutting and snipping device, as shown and described.

DESCRIPTION

FIG. 1 is a top perspective view of a cutting and snipping device shown in accordance with my new design;

FIG. 2 is a bottom perspective view of the cutting and snipping device shown in FIG. 1;

FIG. 3 is a top plan view of the cutting and snipping device shown in FIG. 1;

FIG. 4 is a bottom plan view of the cutting and snipping device shown in FIG. 1;

FIG. 5 is a front elevation view of the cutting and snipping device shown in FIG. 1;

FIG. 6 is a rear elevation view of the cutting and snipping device shown in FIG. 1;

FIG. 7 is a left side elevation view of the cutting and snipping device shown in FIG. 1; and,

FIG. 8 is a right side elevation view of the cutting and snipping device shown in FIG. 1.

The features shown in broken lines are for the purposes of showing portions of the design which form no part of the claimed design.

1 Claim, 6 Drawing Sheets
